UNITED STATES PATENT OFFICE.

JOHN W. MEALY, OF BALTIMORE, MARYLAND, ASSIGNOR TO HENEGEN, BATES & CO., OF SAME PLACE.

DESIGN FOR A SPOON.

SPECIFICATION forming part of Design No. 21,043, dated September 15, 1891.

Application filed April 30, 1891. Serial No. 391,147. Term of patent 3½ years.

To all whom it may concern:

Be it known that I, JOHN W. MEALY, a citizen of the United States, residing at the city of Baltimore, and State of Maryland, have 5 invented and produced a new and original Design for a Spoon; and I do declare the following to be a full, clear, and exact description of the same, reference being had to the accompanying drawings forming a part thereof. 10 The leading features of my design consist in the battle-monument, sprigs of sea-weed, oyster-shells, and a terrapin.

Referring to the drawings, Figure 1 represents a front elevation of the spoon, and Fig. 15 2 a rear view of the same.

A in the drawings represents the battle-monument and is located within the bowl of the spoon. Near the extreme end of the handle is located the terrapin B, and some

distance below the oyster-shells a a. One 20 sprig of sea-weed b is arranged between the oyster-shells and the terrapin, another b' passes partly around the terrapin, and a third sprig b² extends beyond the oyster shells toward the bowl of the spoon. Upon the back 25 of the handle are arranged sprigs of cat-o'-nine tails b⁴, as clearly shown in Fig. 2.

Having described the leading features of my design and their relative positions, what I claim is—

A design for a spoon, substantially as shown and described.

In testimony whereof I affix my signature in presence of two witnesses.

JOHN W. MEALY.

Witnesses:

FRANKLIN MOORE,
W. P. BOTELER.
